UNITED STATES PATENT OFFICE.

NATHANIEL C. HALL, OF OLD LYME, CONNECTICUT.

MOPSTICK.

Application filed June 15, 1922. Serial No. 563,513.

To all whom it may concern:

Be it known that I, NATHANIEL C. HALL, a citizen of the United States, residing at Old Lyme, in the county of New London and State of Connecticut, have invented a new and useful Improvement in Mopsticks; and I do hereby declare the following, when taken in connection with the accompanying drawings and the characters of reference marked thereon, to be a full, clear, and exact description of the same, and which said drawings constitute part of this application, and represent, in—

Fig. 1, a face view of a mop stick constructed in accordance with my invention, showing a dish-cloth connected therewith.

Fig. 2, a side view of the same, partly in section, with the cloth removed.

Fig. 3, a sectional view on the line 3—3 of Fig. 1.

This invention relates to improvement in mop sticks, and particularly for sink or dish-mops. The object of this invention is to provide a stick for holding an ordinary dish-cloth, so that the cloth may be removed and replaced when desired, and the invention consists in the construction as herein-after described and particularly recited in the claims.

In carrying out my invention I employ a shank 5 formed from a rod of metal provided with or attached to a handle 6. Affixed to the outer end of the shank is a head 7 of cork or other suitable material. The shank, near its inner end, is provided with stops 8 formed by upsetting or notching the sides of the shank. Around the shank, below the stops 8, a wire is coiled to form a ring 9, beyond which the ends of the wires extend and beyond the stops the wires are inset, forming shoulders 10, from which the ends 11 and 12 of the wires are outwardly bowed and formed at their outer ends with eyes 13. Around the outer ends of the wires is a slide 14, preferably formed from rubber, with a metal bushing 15. An ordinary dish-cloth 16 is wrapped around the head 7, and the wires moved upward and may be turned on the shank, so that the ends engage with the sides of the cloth, the up-

ward movement of the wires being arrested by the stops 8. The slide 14 is then moved forward so as to clamp the ends of the wires against the cloth below the head, and the eyes form flat surfaces to secure a firm grip upon the cloth. The cloth is thus securely held in place, and the device is used in the ordinary way of a dish mop. With this construction an ordinary dish cloth may be used and when desired may be removed and washed, so that the mop may be kept in a sanitary condition. This device is simple in construction and can be produced at low cost.

I claim:

1. A mop stick comprising a shank, a head mounted on the outer end of said shank, wire arms slidably mounted on said shank for longitudinal movement, and a slide around said shank and arms and adapted to press the outer ends of the arms toward the said shank below the said head, whereby a cloth wrapped around said head will be secured thereto.

2. A mop stick comprising a shank, provided at one end with a handle, a head mounted on the opposite end, wire arms mounted on said shank and rotatably and longitudinally-movable thereon, the outer ends of the arms being outwardly bowed, and a slide around said shank and arms, and adapted to press the outer ends of the arms toward the said shank below said head.

3. A mop stick comprising a shank, provided at one end with a handle and at the opposite end with a head, said shank formed with stops, arms formed from wire wound around said shank beneath said stops, the outer ends of said arms outwardly bowed, and a slide around said arms and adapted to be longitudinally moved thereon to press the outer ends together.

In testimony whereof, I have signed this specification in the presence of two subscribing witnesses.

NATHANIEL C. HALL.

Witnesses:

ROBERT H. NOBLE,
W. H. GRISWOLD.
